G. H. JUERGENS.
WARDROBE TRUNK.
APPLICATION FILED DEC. 14, 1916.

1,223,886.

Patented Apr. 24, 1917.

Inventor,
Gustav H. Juergens.
By Bakewell & Huttons.

UNITED STATES PATENT OFFICE.

GUSTAV H. JUERGENS, OF ST. LOUIS, MISSOURI, ASSIGNOR TO P. C. MURPHY TRUNK CO., OF ST. LOUIS, MISSOURI, A CORPORATION OF MISSOURI.

WARDROBE-TRUNK.

1,223,886.

Specification of Letters Patent. Patented Apr. 24, 1917.

Application filed December 14, 1916. Serial No. 136,883.

To all whom it may concern:

Be it known that I, GUSTAV H. JUERGENS, a citizen of the United States, residing at St. Louis, Missouri, have invented a certain new and useful Improvement in Wardrobe-Trunks, of which the following is a full, clear, and exact description, such as will enable others skilled in the art to which it appertains to make and use the same.

10 This invention relates to wardrobe trunks of the type that are provided with means for locking the two sections of the trunk together at a number of separated points, for example, adjacent the opposite ends of the 15 trunk.

15 The main object of my invention is to provide a wardrobe trunk of the general type referred to, in which the locking mechanism is of simple design and so constructed 20 that the drawers in the drawer section of the trunk do not have to be cut away to form a clearance for any part of the locking mechanism, thereby increasing the drawer space and also reducing the cost of 25 manufacturing the trunk.

To this end I have devised a wardrobe trunk in which the garment section and the drawer section are locked together by a hasp lock arranged adjacent one end of the trunk 30 and provided with a base portion that is oscillatingly mounted on the garment section of the trunk, a sliding bar arranged on the inside of the garment section and connected to the base portion of said hasp lock 35 in such a manner that said bar will be shifted longitudinally when the base portion of said hasp lock is turned or oscillated, and a drawer slide or rail arranged on the drawer section of the trunk adjacent the lower end 40 of the trunk and provided with a hole into which the lower end of said bar projects, so as to securely lock the two sections of the trunk together at a point some distance away from the hasp lock.

45 Figure 1 of the drawings is a vertical sectional view of a wardrobe trunk constructed in accordance with my invention, showing the locking bar on the inside of the trunk in its locked position.

50 Fig. 2 is a similar view, showing said bar in its unlocked position.

Fig. 3 is a horizontal sectional view, taken on the line 3-3 of Fig. 1; and

Fig. 4 is a perspective view illustrating

the locking bar and the drawer slide with 55 which said locking bar coöperates.

Referring to the drawings, which illustrate the preferred form of my invention, A and B designate the garment section and drawer section, respectively, of a wardrobe 60 trunk, C designates a hasp lock arranged adjacent the upper end of the trunk, D designates a locking bar that is slidingly mounted on the inside of the garment section in guides 1 carried by said section, and 65 E designates a drawer slide or rail arranged on the inside of the drawer section adjacent the lower end of the trunk and provided with a hole 2, as shown in Fig. 4, into which the lower end portion of the 70 locking bar D projects when said bar is forced downwardly, as shown in Fig. 1. The hasp lock C, which is of well known construction and arranged on the outside of the trunk, comprises a base portion 3 that 75 is oscillatingly mounted on the garment section A and a hinged portion 4 that is adapted to be moved into engagement with a socket member 5 on the drawer section B. The locking bar D is connected to the base 80 portion 3 of the hasp lock in such a manner that said bar will be moved upwardly when said base portion is turned in one direction and will be moved downwardly when said base portion is turned in the opposite direction, the means that I prefer to use for connecting said parts together consisting of a plate 6 rigidly connected to the inner end of the spindle or pin 7 that pivotally connects the base portion of the hasp lock to the 90 garment section A and studs 8 on the locking bar D that work in elongated slots 9 in the plate 6. The studs 8 and slots 9 are so arranged that a quarter turn of the base portion of the hasp lock in one direction 95 will move the locking bar D upwardly out of engagement with the drawer slide E, and a quarter turn of said base portion in the opposite direction will move said locking bar downwardly its full stroke into locking engagement with said drawer slide. The drawer slide E is preferably formed from angle iron and is made a trifle longer than the other drawer slides E' in the drawer section, so that it will project into the garment section A when the trunk is closed. The hole 2 is formed in the horizontal flange 100 of the drawer slide E, and the lower end

105

portion of the locking bar D is offset slightly at 10, as shown in Fig. 4, so that the lower end of same will be in vertical alinement with the hole 2. The hole 2 can either be 5 made of the same length as the width of the locking bar, or said bar can be provided with a reduced portion 11, as herein shown.

By utilizing one of the drawer slides of 10 the drawer section to form one member of the locking mechanism of the trunk, I overcome the necessity of forming a notch or 15 cut out portion in one of the drawers, and consequently, I increase the drawer space of the trunk and reduce the cost of manufacturing the trunk. Such a locking mechanism can be operated easily; there is little 20 liability of its getting out of order; it can be manufactured cheaply and it securely locks the two sections of the trunk together at both ends of the trunk.

Having thus described my invention, what I claim, and desire to secure by Letters Patent, is:

1. A wardrobe trunk, comprising a 25 garment section and a drawer section, a hasp lock arranged on the outside of the trunk adjacent one end of same and provided with a base portion that is oscillatingly mounted on said garment section, a locking bar arranged on the inside of the trunk and connected to the base portion of said hasp lock in such a manner that said bar will be reciprocated when said base portion is turned, and a drawer slide arranged on the inside 35 of the drawer section adjacent the opposite end of the trunk and provided with a hole into which said locking bar projects when the trunk is locked.

2. A wardrobe trunk, comprising a garment section and a drawer section, a hasp lock arranged on the outside of the trunk adjacent one end of same and provided with a base portion that is oscillatingly mounted on said garment section, a locking bar arranged on the inside of the trunk and connected to the base portion of said hasp lock in such a manner that said bar will be reciprocated when said base portion is turned, a drawer slide arranged on the inside of the drawer section adjacent the opposite end of the trunk and provided with a flange in which a hole is formed, and an offset portion at the lower end of said locking bar that enters said hole when the hasp lock is manipulated to lock the trunk. 55

3. A wardrobe trunk, comprising a garment section and a drawer section, a hasp lock arranged on the outside of the trunk adjacent one end of same and provided with an oscillatingly mounted base portion, a 60 spindle on said base portion that projects through a hole in the garment section, a plate secured to the inner end of said spindle and provided with a pair of elongated slots, a reciprocating locking bar arranged in 65 guides on the inside of the garment section and provided with studs that enter said elongated slots, and an angle-shaped drawer slide arranged on the inside of the drawer section adjacent the opposite end of the 70 trunk and provided with a hole that is adapted to receive a reduced portion on one end of said locking bar when the trunk is locked.

GUSTAV H. JUERGENS.
